UNITED STATES PATENT OFFICE.

URBAIN DRYVERS, OF PARIS, FRANCE.

MECHANICAL PIANO.

1,113,889.

Specification of Letters Patent. Patented Oct. 13, 1914.

Application filed May 12, 1913. Serial No. 767,152.

To all whom it may concern:

Be it known that I, URBAIN DRYVERS, a subject of the King of Belgium, and a resident of Paris, France, (whose post-office address is 3 Rue des Immeubles Industriels, Paris, France,) have invented certain new and useful Improvements in Mechanical Pianos, of which the following is a specification.

10 The present invention relates to an improvement in the roll box for mechanical player pianos, and particularly in a roll box adapted to be mounted in the piano casing and so arranged as to carry the tracker, 15 take-up spool and note sheet supported in such position that the usual piano construction is not materially modified.

It further consists in the support of the take-up spool upon swinging arms which, 20 when the apparatus is not in use, are adapted to be moved into such position that the take-up roll does not project outside the piano casing.

In the accompanying drawings, Figure 1 25 is an elevation of a construction in which my invention is embodied in one form; Fig. 2 is a cross section on the line 2—2, Fig. 1; Fig. 3 is a front elevation of a modified embodiment of my invention; Figs. 4, 30 5 and 6 are cross sections corresponding to Fig. 2, showing the parts in different positions.

In the form shown in Figs. 1 and 2 the apparatus comprises a fixed roll box a 35 adapted to be mounted in the front of the piano casing h and provided in its upper portion with an inwardly extending bay a¹. The note roll b is mounted on the bearings b¹ of ordinary type and fixed in permanent 40 position in the opposite sides of the bay a¹. A tracker c is mounted in fixed position at the angle between the bay a¹ and the lower portion a² of the box which is quite shallow and thus affords ample room for 45 the hammers i. The take-up roll d is carried in bearings at the lower ends of a pair of swinging arms e, pivoted at e¹ adjacent the tracker bar. A bridge piece e² connects the free ends of the arms e and forms a 50 stop which halts the gear d¹ on the spindle of the take-up roll d in operative engagement with the pinion f, which may be driven by any suitable mechanism during the operation of the instrument. In playing position the note sheet g passes from the roll b to the take-up roll d across the face of

the tracker c, in the usual manner. When the player mechanism is not in use, the roll b is removed from its bearings b¹, as usual, and the take-up roll d may then be swung 60 up into the bay a¹, as shown in dotted lines in Fig. 2. In this position it is not only protected against injury, but lies wholly within the confines of the casing h.

In the construction shown in Figs. 3 to 65 6 inclusive, the bearings for the note roll b are carried by a frame a², mounted within the casing h and carrying at its lower portion a tracker c. Adjacent the tracker are the pivots e³ for the arms e⁴ between which 70 the take-up roll d is supported. A cross bar e⁵ unites the lower ends of the arms e⁴ and forms a cradle. In playing position (Fig. 4), the take-up roll bears against a roller k which serves to maintain the note 75 sheet g at constant inclination to the tracker c. The drive of the take-up roll is secured through gearing operated from the shaft j in substantially the same manner as the construction shown in Figs. 1 and 2. When 80 the instrument is not in use the take-up roll is removed from its bearings in the arms e⁴ and substituted for the note roll b in the bearings for the latter in the frame a². The cradle e⁴, e⁵ may either be swung 85 down to the position shown in Fig. 6, or swung up to the position shown in Fig. 5. In either case it lies within the casing h which may have a removable front panel h¹ provided with a notch h², registering 90 with a tracker c and adapted to be fitted in position when the parts are thus arranged.

Various modifications in the details of the arrangement will readily suggest themselves and I do not limit my invention to 95 those shown.

I claim as my invention:—

1. In a player piano a tracker in stationary position, fixed bearings for a note roll and a swinging cradle carrying bearings for the 100 take-up roll, said cradle serving to hold the note sheet upon the tracker during the operation of the instrument but being movable to position wholly within the casing when the player mechanism is not in use, substantially 105 as described.

2. In a player piano, a casing, a roll box fitted in fixed position therein and having in its upper portion an inwardly extending bay, a fixed tracker carried by said 110 roll box and fixed bearings therein for a music roll, in combination with a swinging

cradle having bearings for a take-up roll and pivotally mounted with relation to said roll box so that it may be swung into said inwardly extending bay when the player mechanism is not in use, substantially as described.

In testimony whereof I have signed my

name to this specification, in the presence of two subscribing witnesses.

URBAIN DRYVERS.
